Inventor

JOHN H. HARTMAN.

UNITED STATES PATENT OFFICE.

JOHN H. HARTMAN, OF LANCASTER, PENNSYLVANIA.

DESIGN FOR A TOY OR TOY BANK.

47,421.

Specification for Design.

Patented June 8, 1915.

Application filed March 4, 1915. Serial No. 12,166. Term of patent 3½ years.

To all whom it may concern:

Be it known that I, JOHN H. HARTMAN, a citizen of the United States, residing at Lancaster, in the county of Lancaster and State of Pennsylvania, have invented a new, original, and ornamental Design for Toys or Toy Banks, of which the following is a specification, reference being had to the accompanying drawing, forming part thereof.

Figure 1 represents a front perspective

view of a toy bank, showing my design; and Fig. 2, a side perspective view thereof.

I claim:

The ornamental design for a toy or toy bank, as shown.

JOHN H. HARTMAN.

Witnesses:

JOSEPH P. SHERR,
R. A. REHM.
